ROCKING CHAIR HORSE

William A. Uttz, Fort Worth, Tex.

Application October 24, 1955, Serial No. 38,544

Term of patent 3½ years

(Cl. D34—15)

FIG. 1.

FIG. 2.

FIG. 3.

FIG. 4.

Fig. 1 is a perspective view of a rocking chair horse, showing my new design;

Fig. 2 is a top plan view thereof,

Fig. 3 is a side elevational view thereof,

Fig. 4 is a side elevational view thereof to a reduced scale. The broken line showing in Fig. 4 is for illustrative purposes only.

I claim:

The ornamental design for a rocking chair horse, substantially as shown and described.
